Primary Examiner — Anhdao Doan(74) *Attorney, Agent, or Firm* — Michael Best & Friedrich LLP(57) **CLAIM**

We claim the ornamental design for a bitewing holder, as shown and described.

DESCRIPTION

FIG. 1 is a front perspective view of a bitewing holder.

FIG. 2 is a first side view of the bitewing holder shown in FIG. 1.

FIG. 3 is a second side view of the bitewing holder shown in FIG. 1.

FIG. 4 is a rear view of the bitewing holder shown in FIG. 1.

FIG. 5 is a front view of the bitewing holder shown in FIG. 1.

FIG. 6 is a third side view of the bitewing holder shown in FIG. 1; and,

FIG. 7 is a fourth side view of the bitewing holder shown in FIG. 1.

The broken lines in the drawings are included for the purpose of illustrating portions of the bitewing holder that form no part of the claimed design.
